UNITED STATES PATENT OFFICE.

JOHN BARCLAY, OF PROVIDENCE, RHODE ISLAND.

BAND-BRACELET.

SPECIFICATION forming part of Letters Patent No. 289,371, dated December 4, 1883.

Application filed September 3, 1883. (No model.)

To all whom it may concern:

Be it known that I, JOHN BARCLAY, of the city and county of Providence, State of Rhode Island, have invented a new and useful Improvement in Band-Bracelets; and I hereby declare the following to be a full, clear, and exact description of the same, reference being had to the accompanying drawings, forming part of this specification.

10 This invention has reference to an improvement in the construction of flexible band-bracelets; and it consists in the peculiar and novel construction by which the edge of the band is turned over and under, as will be more 15 fully set forth hereinafter.

15 In the construction of band-bracelets made of a thin strip of plated stock, in which the two sides of the sheet metal are protected by a layer of precious metal, the edges of the inferior metal are exposed, and are soon affected by oxidation.

20 The object of this invention is to protect these edges, produce a rounded edge and slightly-raised border, without materially increasing the stiffness of the band.

25 Figure 1 is a perspective view of my improved band-bracelet. Fig. 2 is an end view of a ring provided with a loop or band having turned-over edges. Fig. 3 is a sectional view 30 of the band, showing the edges turned over; and Fig. 4 is a sectional view of the rolled-down and finished edges.

35 In the drawings, A is the band, made of stock-plate or a sheet of inferior metal plated with precious metal on each side—a well-known article used by jewelers in the manufacture of plated jewelry.

b b are the edges of the band. The edges

are first turned over and under, as is shown in Fig. 3. They are then flattened between rolls, as is shown in Fig. 4, presenting a rounded edge and flat border on each edge of the band. By this construction the strength of the band is increased and a thicker rounded edge produced; but the flexibility of the band is not materially affected. It can be readily formed into bands and bracelets, presents a durable appearance, and the raised border protects the ornamental center of the band A against injury.

30 I am aware that the edges of bracelets have before my present invention been turned up and over, both to increase the thickness of the edge and to protect the edge of the plated metal; but such turned-up edges could only be used on winged or rigid bracelets, as they formed a truss which stiffened the plate. By rolling the turned-up and under edges down flat, as is shown in Fig. 4, the flexibility of the band is not materially affected, and it can be used for band-bracelets and similar articles.

Having thus described my invention, I claim as new and desire to secure by Letters Patent—

1. A band-bracelet having its edges turned over so as to form a flat raised band and rounded edges, as described, as a new article of manufacture.

2. The combination, with the band A, of the turned over and under compressed flattened edges *b b*, constructed to protect the edges, as described.

JOHN BARCLAY.
